Primary Examiner — Darcey E Gottschalk*Assistant Examiner* — Haley K Schnebele(74) *Attorney, Agent, or Firm* — Daniel M. Cohn;
Howard M. Cohn(57) **CLAIM**

The ornamental design for a soap dispenser, as shown and described.

DESCRIPTION

FIG. 1 is a top, front and right side perspective view of a soap dispenser showing my new design;

FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof; and,

FIG. 8 is an enlarged bottom plan view thereof.

The broken lines in the drawings illustrate portions of the soap dispenser that form no part of the claimed design.
